UNITED STATES PATENT OFFICE.

HENRY C. MILLER, OF MILWAUKEE, WISCONSIN.

LOOSE-LEAF BINDER.

1,201,214.

Specification of Letters Patent. Patented Oct. 10, 1916.

Application filed June 5, 1915. Serial No. 32,317.

To all whom it may concern:

Be it known that I, HENRY C. MILLER, a citizen of the United States, and resident of Milwaukee, in the county of Milwaukee and State of Wisconsin, have invented new and useful Improvements in Loose-Leaf Binders, of which the following is a description, reference being had to the accompanying drawings, which are a part of this specification.

This invention relates to improvements in loose leaf binders and more particularly to that type in which the leaves are removably locked to the cover and back by hinged prongs.

It is one of the objects of the present invention to provide a loose leaf binder in which the prongs are held firmly in locked position and may be easily swung to open position to release the leaves.

A further object of the invention is to provide a loose leaf binder having a simple means for attaching the prongs and connected parts to the cover and back portion of the binder.

A further object of the invention is to provide a loose leaf binder which is of simple construction, is strong and durable and is well adapted for the purpose described.

With the above and other objects in view the invention relates to the improved loose leaf binder and its parts and combinations as set forth in the claims and all equivalents thereof.

In the accompanying drawings in which the same reference characters indicate the same parts in all of the views:

Figure 1 is a top view of a portion of the improved loose leaf binder, the binder being shown in open position; Fig. 2 is a transverse sectional view thereof taken on line 2-2 of Fig. 1; Fig. 3 is a similar view taken on line 3-3 of Fig. 1; Fig. 4 is a longitudinal sectional detail view taken on line 4-4 of Fig. 1; Fig. 5 is a transverse sectional detail view of a modified form of binder; Fig. 6 is a top view of another modified form of binder; Fig. 7 is a transverse sectional detail view thereof taken on line 7-7 of Fig. 6; Fig. 8 is a top view of a portion of a modified form of binder, the binder being shown in open position; Fig. 9 is a transverse sectional view thereof taken on line 9-9 of Fig. 8; Fig. 10 is a transverse sectional detail view taken on line 10-10 of Fig. 8; Fig. 11 is a similar view taken

on line 11-11 of Fig. 8; Fig. 12 is a longitudinal sectional detail view taken on line 12-12 of Fig. 8, the prongs being shown as in closed position; and Fig. 13 is a similar view with the prongs being shown as in open position.

Referring to the drawings the numeral 15 indicates the cover which comprises the side portions 16 joined together by the back portion 17. A pair of prong or hook plates 18 are positioned adjacent to the back portion and have their inner edges hingedly connected together by angular tie members 19 which are engaged by notched portions 20 of the prong plates. The prong plates are held yieldingly in open or closed position by spring members 21 having hooked end portions 21' which hook over notched portions 18' of the outer edges of the prong plates. The medial portions of the spring members are coiled or looped as indicated by the numeral 22 to permit the use of longer springs than could otherwise be used and to also provide means for removably securing the spring members to the cover back.

In constructing the cover back 17 a metal reinforcing plate 23 is interposed between and attached to the thicknesses of the material of the cover back and is provided with projecting eyed portions 24 which overlap the plane of the spring loops and a locking bar 25 extends through the loops 22 and the eyed portions 24 and removably locks the parts together. The locking bar may be withdrawn endwise to disengage the parts.

Semicircular shaped prongs 26 are mounted in pairs on the prong plates and their upper free ends overlap each other when in closed position to form a circular leaf holding means for holding removable leaves A. As the inner edges of the prong plates swing above and below the plane of connection of the springs with the outer edges of the plates, the plates will be yieldingly held in their upper or lower position and the prongs mounted thereon in either open or closed position. The angular faces 19' of the tie members 19 serve to limit the upper and lower movement of the plates, and when in their lower position the upper ends of the curved prongs partly overlap and abut against each other. While the prongs may be swung to open position by pulling the prongs apart, it has been found more desirable to provide

a push button means for accomplishing the same result. This means comprises a bell crank lever 27 which is interposed between the cover back and the prong plates and is 5 pivotally connected to said cover back. The short arm 28 of the lever engages the inner edge portions of the prong plates and the outer end of the long arm 28' projects outwardly from the cover back and is adapted 10 to be pressed downwardly to swing the short arm upwardly and the prong plates to open position.

In the modified form shown in Fig. 5 the 15 spring 29 is slightly different from the springs 21 in that it extends over the upper portions of the prong plates and its loop 30 depends through an opening 31' formed between the said prong plates. The locking bar 25 extends through the loop in the same 20 manner as before described to lock the plates to the cover back.

In the Figs. 5 and 6 modified forms the outer edge portions of the prong plates are bent to form eyed portions 32 through which 25 extend pintle hinge pins 33. The outer edge portions of the prong plates are notched as indicated by the numeral 34 to expose the pintle pins and to accommodate the eyed ends 35 of the spring members 21 and form 30 a hinge connection therebetween.

In the modified forms illustrated in Figs. 8 to 13 inclusive, the use of spring members is eliminated and in lieu thereof a slidable locking member is provided which may be 35 moved to open or close the prongs. The slidable member 36 is provided with angularly disposed grooves or recesses 37 which incline downwardly toward each other at their outer end portions as shown in Fig. 10. 40 From the outer end portions, in a direction toward the inner end of the member, the inclination of the grooves or recesses gradually change and at the inner end of the member the grooves extend upwardly toward each 45 other as shown in Fig. 11. The adjacent ends of the prong plates are adapted to enter the grooves of the locking member when said member is pushed inwardly and in entering the grooves the prong plates will be 50 forced downwardly to closed position and locked in said position while the locking member is in closed position.

In order to permit the prong plates to swing to open and closed positions the outer 55 edge portions of said plates are engaged by the bent edges 38 of a rigid back plate 39. The said back plate is connected to the cover back in the same manner before described by one or more locking bars 25'.

60 The back plate at a medial point is provided with an upstanding angularly bent portion or bump 40 which inclines upwardly toward the locking member and at its upper surface is provided with a flat portion 41. 65 Immediately above the angular portion 40

the abutting edges of the prong plates are cut away to form an elongated opening 42 to receive the grooved portion of a slidable wedge member 43 which is adapted to swing the prong plates to open position. The 70 wedge member is linked to a wire loop 44 which forms part of and projects inwardly from the locking member and is moved thereby. The wedge member is positioned with its inclined portion 45 adjacent to the 75 angular face of the bent portion 40 so that as the locking member is pulled outwardly to unlock the prong plates the wedge member will ride up the angular bump 40 and swing the prong plates to open position. 80 When in open position the lower flat portion 44 of the wedge member will rest upon the upper flat portion of the bump and the parts will remain in open position.

For convenience in operating the locking 85 member, it is provided with a flat end plate 36' which may be easily engaged by the finger of the user to open or close the prongs.

From the foregoing description it will be seen that the loose leaf binder is of very 90 simple construction and is well adapted for the purpose described.

What I claim as my invention is:

1. A loose leaf binder, comprising a pair 95 of plates having leaf holding prongs projecting therefrom, means interposed between the plates for hingedly connecting the inner longitudinal edge portions of the plates together, a plurality of yielding members having bent end portions which extend over the 100 outer longitudinal edges of the plates for holding the plates in open or closed position, and means engaging the yielding members for attaching the plates to a cover back.

2. A loose leaf binder, comprising a pair 105 of plates having leaf holding prongs projecting therefrom, means for hingedly connecting the inner longitudinal edge portions of the plates together, a plurality of looped springs having bent end portions which engage 110 the outer edge portions of the plates for holding the plates in open or closed position, and means for engaging the spring loops for attaching the plates to a cover back.

3. A loose leaf binder, comprising a pair 115 of plates having leaf holding prongs projecting therefrom, means for hingedly connecting the inner longitudinal edge portions of the plates together, a plurality of looped springs having bent end portions which engage 120 the outer edge portions of the plates for holding the plates in open or closed position, and a locking bar extending through the loops for attaching the plates to the cover back.

4. A loose leaf binder, comprising a pair 125 of plates having leaf holding prongs projecting therefrom, means for hingedly connecting the inner longitudinal edge portions of the plates together and limiting their 130

- movements to open or closed position, a plurality of looped springs having bent end portions which engage the outer edge portions of the plates for yieldingly holding the plates in open or closed position, a reinforcing plate for attachment to a book cover, and a locking bar engaging the reinforcing plate and the loops of the springs for connecting the parts together.
- 5 5. A loose leaf binder, comprising a pair of plates having leaf holding prongs projecting therefrom, means for hingedly connecting the inner longitudinal edge portions of the plates together and limiting their movements to open or closed position, a plurality of looped springs having bent end portions which engage the outer edge portions of the plates for yieldingly holding the plates in open or closed position, a reinforcing plate for attachment to a book cover and having upwardly projecting eyed portions, and a locking bar extending through the plate eyes and the spring loops for connecting the parts together.
- 10 6. A loose leaf binder, comprising a pair of plates having leaf holding prongs projecting therefrom, angular tie members hingedly connecting the inner edge portions of the plates together, a plurality of looped springs having bent end portions which engage notched edge portions of the outer
- 15 edge portions of the plates for yieldingly holding the plates in open or closed position, a reinforcing plate for attachment to a book cover and having upwardly projecting eyed portions which overlap the loops of the springs, and a locking bar extending through the plate eyes and the spring loops for connecting the parts together.
- 20 7. A loose leaf binder, comprising a pair of notched plates having leaf holding prongs projecting therefrom, the outer edge portions of said plates being folded over to form eyed portions, rods extending through said eyes, a plurality of transversely extending looped springs having bent ends which engage the wires to yieldingly hold the plates in open and closed position, angular tie members interposed between and hingedly connecting the inner edge portions of the plates together, a reinforcing plate adapted to be connected to a cover back and having eyed portions projecting therefrom, and a locking bar extending through the eyed portions and the spring loops.
- 25 In testimony whereof, I affix my signature, in presence of two witnesses.
- 30 HENRY C. MILLER.
